UNITED STATES PATENT OFFICE.

ELLIOT STEWART, OF BROOKLYN, NEW YORK.

PRACTICE-KEYBOARD FOR TYPEWRITING.

1,331,728.

Specification of Letters Patent. Patented Feb. 24, 1920.

Application filed November 27, 1918. Serial No. 264,402.

To all whom it may concern:

Be it known that I, ELLIOT STEWART, a citizen of the United States, and resident of Brooklyn, N. Y., have invented certain new and useful Improvements in Practice-Keyboards for Typewriting, of which the following is a specification.

My invention relates to keyboards for acquiring the art of typewriting.

10 One object of this invention is to provide a simple and inexpensive keyboard which will display a corresponding letter whenever a key is depressed. In a practice device of this kind economy is a main consideration.

15 In my keyboard the keys are pins moving in holes in a block of wood, and aside from these keys, there are only ten moving parts, pivoted on a single rod, and these parts can be easily sawed out of wood. I attain simplicity of construction by (a) having the key-bars serve both to support the keys, and to carry the letters; (b) having each key-bar serve for three keys, instead of only one; (c) controlling the motion of the key-bar, so that only one of the three letters which it carries is brought into view when a key is depressed.

In carrying my invention into effect I provide a keyboard which simulates that of 30 the standard typewriter in so far that the keys are arranged in a plurality of parallel rows at different elevations, those at the rear being highest and those toward the front being stepped down in succession, the keys of 35 each row being staggered in relation to those of the adjacent rows substantially as in the ordinary typewriter.

The invention is shown in the accompanying drawings, in which,

40 Figure 1 is a plan of the keyboard with part of the top cut away.

Fig. 2 is a vertical section.

Fig. 3 is a section showing the position of the parts when the lower key is depressed.

45 Fig. 4 is a section with the middle key depressed and,

Fig. 5 is a section with the upper key depressed.

1 is the case or frame of the keyboard; 2 50 the top of the case, 3 a strip attached under the top, 4 a strip parallel to the edge of the top and to strip 3. The top 2 and strip 3 on one side and strip 4 on the other side form the slot 5, at which the letters appear. 6 is 55 a rod or shaft with its ends supported by the frame. 7 is the key-holder, 8 the space-bar,

which is immovably attached to the key-holder. 9, 10, 11, 12, 13 and 14 are keys which pass through holes in the key-holder. 15, 16, 17, 18 and 19 are keybars pivoted on 60 the shaft 6. 20 are pins which separate the key-bars and hold them in proper position. The key-bars as above described serve as carriers for the characters to be displayed.

Fig. 2 is a sectional view through M—M, 65 Fig. 1, with the key-holder 7 cut away to expose the keys 12, 13, and 14. The key-bar 19 is pivoted on the rod 6. The hole in the key-bar is somewhat larger than the rod, in order to allow the key-bar the freedom 70 of movement necessary for it to rotate in its own vertical plane. The keys 12, 13 and 14 pass through holes in the key-holder 7, and their lower ends rest on the key-bar 19. The rear part of key-bar 19 is of such 75 form and its pivot is so located that the force of gravity causes the rear edge of key-bar 19 normally to rest on the bottom of the case. The top of key-bar 19 is marked with three letters T, G, and B, which are 80 concealed by the strip 3 and the top 2, when the key-bar or letter carrier is in normal position.

In Fig. 1 parts of the top 2, and of the strips 3 and 4 are cut away, exposing the 85 key-bars 15, 16, 17, 18, and 19. Key-bars 15 and 19 are shown in normal position. Key-bar 16 is shown in position when its lower key 9 is depressed. Of the three letters W, S, and X which key bar 16 carries 90 on its top, the front letter X, which corresponds to key 9 is brought into view opposite the slot 5, and W and S are concealed under strip 3. Key-bar 17 is shown with its middle key 10 depressed. The 95 middle letter D, corresponding to the middle key 10 is brought into view, letter E is concealed under strip 3, and letter C is concealed under strip 4. Key-bar 18 is shown with its upper key 11 depressed. The rear 100 letter R, corresponding to the upper key 11 is brought into view, and the other two concealed under strip 4. The other key-bars and keys operate in the same manner.

Figs. 3, 4 and 5 are sectional views similar to Fig. 2, but showing the parts in different positions when keys 12, 13, and 14, respectively, are depressed.

In Fig. 3 key 12 is depressed until its top rests on the surface of the key-holder 7. 110 This movement rotates key-bar 19 around rod 6 through an angle of about five de-

grees with respect to the normal position of Fig. 2, and brings the letter B (Fig. 1) which is marked on its top into view opposite slot 5. In this movement keys 13 and 5 14 also fall slightly because they rest on key-bar 19.

In Fig. 4, key 13 is depressed until its top rests on the surface of key-holder 7. Key 12 remains suspended as in Fig. 3. 10 Key-bar 19 is rotated about ten degrees beyond its normal position in Fig. 2, bringing into view the letter G (Fig. 1), corresponding to key 13.

In Fig. 5, key 14 is depressed until the 15 front edge of key-bar 19 rests on the bottom of the case. Keys 12 and 13 remain suspended as in Fig. 4. Key-bar 19 is rotated about fifteen degrees beyond its normal position in Fig. 2, bringing into view the letter 20 T (Fig. 1), corresponding to key 14.

In my invention, as applied to the model herein described, a single key-bar carries three letters, supports three keys, and may be actuated by depressing any one of the 25 three keys, whereupon only one letter is brought into view, corresponding to the key which is depressed. The same principles may be applied to other keyboards wherein the key-bars may support a different number 30 of keys, as two or four, or may carry numbers or other characters instead of letters.

It will be observed that the inclined position of the key-bars or character carriers 35 correspond to the set of keys, as for instance 12, 13 and 14 which are to operate the carrier respectively and the carriers turn in these inclined planes. This arrangement contributes materially to the 40 simplicity of the structure.

In the appended claims reference is made to a set of keys. In doing so I refer to a number of keys, three in the present organization, which operate upon the same arm 45 and move the same character carrier.

What I claim is:

1. In combination a frame, a plurality of character carriers rotatably mounted on a horizontal axis and each having an arm 50 rigidly connected therewith, to move as one body with the carrier about the said horizontal axis, which is common to said carriers and other rigid arms, and keys having stems mounted and guided in the frame 55 resting on said arms and when depressed turning the carriers about the horizontal axis, substantially as described.

2. In combination a frame, a plurality of character carriers pivotally mounted in the 60 frame, each having a forwardly extending arm connected rigidly therewith, a key holder and sets of keys held thereby, the stems of the keys of each set resting on the arm of a carrier and being held elevated 65 thereby, one being located over the forward

end of the arm in respect to the other keys of the set, the forward keys of each set being limited in their downward movement by contacting with the top of the key holder.

3. In combination a casing, a set of keys 70 at the front thereof, a character carrier arranged in the casing and pivotally mounted, said carrier having a preponderance of weight in rear of its pivot and being normally in a retracted position away from the 75 keys and at the back of the casing, said carrier having a rigid forwardly extending arm, stems for the keys overlying said arm, said carrier having its characters on its upper edge and facing upwardly, the depression of said keys turning the carrier through different degrees of angular movement to bring different characters thereon to a display point.

4. In combination a plurality of pivoted 85 character carriers, each having a preponderance of weight in rear of its pivot and having a forwardly extending arm connected rigidly therewith, a key holder and keys held thereby, the stems of which rest on the 90 arms of the carriers and are held elevated thereby, certain of said key stems having means thereon to strike on top of the key holder to limit the downward movement thereof.

5. In combination a plurality of character carriers, sets of keys for operating the several carriers, the keys of each set being arranged in a row whereby one is located forwardly in relation to the others of the same 100 set, one set for each carrier, and a key holder in which the key stems are mounted having an inclined upper surface above which the different keys of each set which operate a particular carrier extend for unequal distances, when in a retracted position, said upper surface serving as a stop for the downward movement of the forward keys in each set.

6. In combination, a key-board having 110 keys in rows, those of one row being staggered in relation to those of other rows, and character carriers, each of which is operable from a plurality of keys, one in each row, said carriers being inclined laterally in respect to the vertical planes in which the rows of keys lie and to correspond with the vertical plane in which the set of keys lies, one in each row, which operate any particular carrier, substantially as described.

7. In combination a keyboard having 120 keys in rows, those of one row being staggered in relation to those of other rows, and character carriers, each of which is operable from a plurality of keys, one in each row, 125 said carriers being inclined laterally in respect to the vertical planes in which the rows of keys lie and to correspond with the vertical planes in which the set of keys lies, one in each row, which operate the carriers, said 130

carriers being pivotally mounted, substantially as described.

8. In combination a plurality of rows of keys at different elevations, the keys of one row being staggered in relation to those of other rows, and carriers having each a plurality of characters thereon to be brought to a display point, said carriers being inclined laterally in respect to the vertical planes in which the rows of keys lie and each having a portion extending under a key of each row to be operated thereby, the lateral incline of the carrier corresponding substantially to the inclined arrangement of the set of keys which is to operate it, substantially as described.

9. In combination, a frame, a character carrier pivotally mounted in the frame and having an arm connected integrally thereto and having a preponderance of weight in rear of its pivot and adapted to assume a retracted position by gravity, said carrier turning toward the front of the machine when its integral arm is pressed down, and

having a plurality of characters, and a plurality of keys having stems mounted in the frame for operating the carrier by pressing its integral arm down, said keys respectively turning said carrier to different angular positions, and a casing having a display opening to which the characters are brought by the forward turning movement of the carrier, substantially as described. 25 30

10. In combination a plurality of rows of keys, the keys of one row being staggered in relation to those of other rows, and carriers having each a plurality of characters thereon to be brought to a display point, and each having a portion rigidly connected therewith and extending under a key of each row to be operated thereby, said extended portion being inclined laterally in respect to the vertical planes in which the rows of keys lie, and to correspond with the vertical plane in which the set of keys lies, one in each row, 40 45 which operate any particular carrier.

In testimony whereof, I affix my signature.
ELLIOT STEWART.
